ELECTRON DISCHARGE TUBE WITH METAL FOIL ELECTRODE

Johan Lodewijk Hendrik Jonker and Gesinus Diemer, Eindhoven, Netherlands, assignors to Hartford National Bank and Trust Company, Hartford, Conn., as trustee

Application August 17, 1946, Serial No. 691,334
In Belgium May 1, 1945

Section 1, Public Law 690, August 8, 1946
Patent expires May 1, 1965

4 Claims. (Cl. 250—27.5)

1

This invention relates to an electric discharge tube having an electrode system which comprises at least a cathode, an anode and one or more intermediate auxiliary electrodes.

These auxiliary electrodes, for instance, control- and screen-electrodes, are usually shaped as a wire-grid consisting of a certain number of thin wires spaced apart from each other, thus leaving apertures for the passage of electrons. In this case the grid must be designed in such a manner as to be capable of acting sufficiently upon the electron stream by voltage variations. Furthermore, notably in the case of screen grids, the ratio between the surface area of the apertures and that of the wires must be such that not too many electrons are intercepted and flow off as screen-grid current, such a grid nevertheless having to function as an electrostatic screen between the electrodes located at both sides thereof. In many cases a compromise has to be arrived at in determining the size of the apertures of the grid and the thickness of the wires. Of course, one is bound to the mechanical possibilities of working up such grids.

Very satisfactory results are obtained by making use of an electric discharge tube according to the invention, the electrode system of which consists of a cathode, an anode and one or more intermediate auxiliary electrodes, one auxiliary electrode consisting at least partly of a thin metal film.

When making use of this construction a complete electrostatic shielding is obtained and the permeability to electrons is quite satisfactory. Therefore this construction is particularly suitable for use in the case of screen grids, though it is also feasible, for instance in transmitting tubes, to design control-electrodes in this way. For acting upon the electron stream these electrodes, which consist of a metal film, yield a very uniform field, since there are no apertures through which extends the field of a neighbouring electrode.

The film must be very thin and be made from suitable material. As such we may mention metals, for instance gold, nickel, copper and silver, the last-mentioned metal more particularly giving excellent results. The thickness of the film should not exceed 0.2μ . For instance, it has been

found that when making use of a silver film having a thickness of about 0.1μ the permeability to electrons amounts to 30 to 50% when applying a voltage of $+3$ to the film. More particularly at these low voltages the electron permeability is high.

These films can be made in a manner known. According to a very suitable method, a film is secured to a frame, for instance grid-shaped, to constitute the support, from a chemical bath on which a very thin layer of silver deposits, which constitutes the film proper, by immersion of the frame, after which it is lifted under the film so that the latter rests on the frame. If desired, this may take place by siphonage of the liquid.

According to another known method, a nickel-film is precipitated electrolytically or by vaporisation on a polished steelplate, whereafter the steelplate is solved chemically. Instead of a steelplate, one can use a Celluloid plate. Then the metal film is applied to a frame and eventually glued.

What we claim is:

1. An electron discharge tube comprising a cathode, an anode and an auxiliary electrode interposed between said cathode and anode, said auxiliary electrode comprising a metal foil having a thickness of the order about 0.1μ to 0.2μ and having at potentials thereof of the order of 3 volts positive relative to said cathode an electron permeability of the order of 30% to 50%.

2. An electron discharge tube comprising a cathode, an anode, a control grid interposed between the cathode and anode, and a screen grid interposed between said control grid and said anode, said screen grid comprising a metal foil having a thickness of the order of 0.1μ to 0.2μ and having at potentials thereof of the order of 3 volts positive relative to said cathode an electron permeability of the order of 30% to 50%.

3. An electron discharge tube comprising a cathode, an anode and an auxiliary electrode interposed between said cathode and anode, said auxiliary electrode comprising a silver foil having a thickness of the order of about 0.1μ and having at potentials thereof of the order of 3 volts positive relative to the cathode an electron permeability of the order of 30% to 50%.

4. An electron discharge tube comprising a cathode, an anode, a control grid interposed be-

tween the cathode and anode, and a screen grid interposed between the control grid and the anode, said screen grid comprising a foil of a metal selected from the group consisting of gold, copper and silver, said foil having a thickness of the order of about 0.1μ to 0.2μ and having at potentials thereof of the order of 3 volts positive relative to said cathode an electron permeability of the order of 30% to 50%.
